UNITED STATES PATENT OFFICE

ROY EMERY, OF BROOKLYN, NEW YORK

SELECTIVE MECHANISM

Application filed November 4, 1926. Serial No. 146,270.

This invention relates to selective releasing mechanism of the same general character as that embodied in my pending application for Letters Patent for selective mechanism, filed June 23, 1925, Serial No. 39,155; and in Patents No. 1,722,370, releasing means for typographical machines, dated July 30, 1929, and No. 1,763,425, selective mechanism, dated June 10, 1930.

10. The objects of this invention are: To provide means for actuating a timed escapement of the form now in general use in circulating-matrix typographical machines, in conjunction with the combination lock keyboard mechanism described in the abovementioned application and patents; to provide an escapement which will eject matrices from a magazine; to provide escapement operating mechanism which may be placed either above 15 or below a magazine; to provide a form of movable selective releasing rods which will give the maximum movement of the releasing bars or reed elements while the rods are given a minimum movement, and to provide a releasing mechanism of the character described with a minimum number of parts.

With these and other objects in view reference may now be had to the drawings forming a part of this specification.

30. Referring to the drawings forming a part of this specification, in which similar reference characters refer to similar parts throughout the several views of the drawings.

35. Fig. 1 is a plan of a magazine of a typographical machine in which the channel arrangement may be assumed to be of the standard form, a part thereof being broken away, to which is shown applied my releasing means; Fig. 2 is a fragmentary view of the releasing means showing the mechanism disposed above the magazine; Fig. 3 is a fragmentary sectional view of Fig. 1; Fig. 4 is a front view of the magazine, a portion thereof being broken away, to show the releasing means and the manner in which the same is connected with the actuating mechanism thereof; Fig. 5 is a vertical sectional view of the electromagnets by which the releasing 40 rods are actuated (said view is taken on line

5—5 of Fig. 7.) Fig. 6 is an end view of a portion of the magazine with my improved releasing means applied thereto; Fig. 7 is a partial vertical sectional view of the electromagnets on line 7—7 of Fig. 5; Fig. 8 is a fragmentary plan of a magazine with a modified form of my releasing means applied thereto; Fig. 9 is a sectional view of the releasing means and the magazine, illustrating a modified form thereof; Fig. 10 is sectional view showing a further modification of the releasing means; Fig. 11 is a detail perspective view of the releasing bar of Fig. 9 to which is attached the releasing cam; Fig. 12 is a detail perspective view of the cam which is mounted 55 in the releasing bar shown in Figs. 9 and 11; Fig. 13 is a transverse sectional view taken on line 13—13 of Fig. 9; Fig. 14 is a detail showing the manner in which the releasing bars operate to release a matrix from 60 the magazine; Fig. 15 is a detail view similar to that shown in Fig. 14, but showing the releasing rods and bars in the tripped position, as when releasing a matrix from the magazine; Fig. 16 is detail view showing 65 how the rods shown in Fig. 14 act when rotated as required in actuating other releasing bars, than the one shown in the drawing; Fig. 17 is a view of a modified form of the releasing bar and releasing rods, wherein 70 quicker action in releasing and locking the bars against release is possible; Fig. 18 is a similar view to that shown in Fig. 17, showing the members in different positions of adjustment, and Fig. 19 is a similar view to 75 Figs. 17 and 18, illustrating a still different position of the parts.

In the drawings, the numeral 100 indicates the magazine; 110, 120, 130, 140, 150, 160 and 170 releasing rods, 180 and 190 are parts 80 of a bearing frame for the releasing rods, and other parts, and 180a and 190a are retaining members for the ends of the releasing rods, 110 to 170 &c. The said rods are reduced at their ends as shown by dotted lines 85 at 111, 121, 131, 141, 151, 161, 171, by which their longitudinal movement to the left is limited. Each of said rods is held by a spring, as 112, 122, 132, 142, 152, 162, and 172, so that when released after rotation it is 90 95 100

immediately restored to the normal position. The said springs are firmly secured by pins in the rods at one end and the other ends are seated in an opening provided in the plate 180a. The opposite ends of the releasing rods 5 are rotatably supported in the bearing member 190a. The ends of said rods are squared as indicated at 113, 123, 133, 143, 153, 163 and 173 and on each rod is a crank member 10 as 114, 124, 134, 144, 154, 164 and 174. In each of said crank members is a stud, as 115, 125, 135, 145, 155, 165, and 175. Beginning at the rod, 110, the next rod, 120, is a little longer, the difference being equal to the thickness of 15 the crank, as 114; and accordingly each succeeding rod increases in length by the same rule, so that the said crank members, extend beyond the next rod and preceding crank, as for example the crank 124 extends 20 beyond the end of the rod 110 and serves as a means of retaining the crank 114 upon the end of said rod 110. All of the cranks and rods are arranged in like manner, but on the end of the rod 170, as at 173, a binder, 25 176, is keyed on to the end of the rod after the crank, as 174, is in position, as rod 160 is the last of the series there is no crank to overlap crank 174 to retain it in position; therefore this binder is required.

30 There are cranking elements for actuating said cranks, one for each crank, designated as 210, 220, 230, 240, 250, 260 and 270, each having a horizontal shoulder, as 211, 221, 231, 241, 251, 261 and 271, which engage the 35 studs as 115 and 125 &c., of the crank members as 114 and 124 &c., and above the shoulder and to the rear of the stud resting thereon, is an extension on each of said cranking elements as 212, 222, 232, 242, 252, 262, and 272. The extensions are each guided and kept in 40 position, by the adjacent crank member, the next adjacent cranking element, and by the stud in the crank member, in the front, and by the arc-shaped surface of the next crank 45 members; for example, the cranking element 211, rests against the crank member 111, on one side, the cranking element 222 on the other side, and the stud 115, engages the front edge of the extension 212, and the arc-shaped surface of the crank member 121 50 engages said extension on its rear edge. In like manner each of the cranking elements are guided in their respective positions. In the case of the cranking element 270, which 55 is the last of the series, it is engaged by one crank member 171 and the stud 175, but there is no adjacent crank member or cranking element to engage the other two sides, so a collar 177, takes the place of the arc-shaped 60 surface of the succeeding crank members which serve to engage and retain the vertical extensions of the other cranking elements, and the binder 176 serves to retain the vertical extension 172, in its position in the 65 place of an adjacent cranking element, as

in the case of all the other cranking elements. When a crank member is raised so as to rotate the rod on which it is held, the springs hereinbefore described immediately restore the rod to its normal position, forcing the cranking element back into normal position also in readiness to be actuated again.

Attention is directed to Figures 5 and 7 of the drawings illustrating the motive agency by which the releasing means is actuated.

In Figure 5, is shown two of a series of electro-magnets mounted upon suitable supports in a housing; the wiring system and generating means not being shown. The magnets are designated 310, 320, 330, 340, 350, 360 and 370 and are mounted on bars, as 300a and 300b supported upon walls of the housing 300. Hinged doors to the housing are provided at the front and the rear as 301 and 302 so that the magnets are readily accessible for installation, or repairs or removal. Magnetically controlled levers, 311, 321, 331, 341, 351, 361 and 371, are provided and pivotally mounted adjacent the magnets. On the end of each of said levers is a U-shaped bearing 312, 322, 332, 342, 352, 362 and 372, in which is held a pin 313, 323, 333, 343, 353, 363 and 373 of rods 314, 324, 334, 344, 354, 364, and 374, each of which have their upper ends threaded into a turn-buckle, as at 315, 325, 335, 345, 355, 365 and 375, only a part of said rods and turn-buckles are shown in the drawings. In the opposite ends of the turn-buckles are the ends of the rods, or cranking elements 210, 220, 230, 240, 250, 260 and 270. By means of the turn buckles, the length of the said cranking elements may be properly adjusted. Slots, as 314a, 324a, &c. are provided for the vertical rods, 314, 324 &c. in the upper wall of the housing, and the door 301 when closed prevents the rods from being displaced, but when the said door is opened, the pins, as 313, 323 &c. can be readily removed from the U-shaped bearings, as 312, 322, &c. The lower end of the said rods and connected cranking elements, being free, the cranking elements can be withdrawn from their position for actuating the releasing rods.

By means not here shown and not embodied in this application, the magnets herein shown are actuated in combination in series of one to seven, whereby a different release in the magazine is actuated for the release of a particular matrix, with each change in the combination of members actuated. The magnets being all actuated by the same current, as many as are actuated with each operation will act in unison, thereby actuating in unison, one, two or more rods, whereby the releasing means are actuated for the release and ejection of a matrix from the required channel of the magazine.

The turn-buckles and rods on which they are disposed, 314, 324, &c. are arranged in a vertical plane at a right angle with the levers

as 311, 321 &c., but the cranking elements are offset as at 210a, 220a, 230a, 250a, 260a and 270a as shown in Fig. 4, to accommodate the inclination of the magazine and the difference in the length of the releasing rods, 110, 120 to 170.

In Fig. 2 of the drawings I have shown the releasing mechanism controlled by the releasing rods, 110, 120 to 170, &c. The magazine 100 includes the upper plate 100a and a lower plate 100b. The lower plate 100b has an extension, 100c, which is slightly curved at 100d, and channelled at 100e and at 100f, the object of which will be presently explained. A reenforcing plate 100g is disposed beneath the extension plate 100c. The upper plate 100a is curved as at 100h, to correspond with the curved extension plate 100c and a recess 100i is provided therein to admit the releasing pawl, 1000, held upon the fulcrum 102, which is a rod extending entirely across the magazine and serving as a fulcrum for all the corresponding pawls, for the entire number of channels of the magazine some ninety in number, but not all shown in the drawings, all of them being the same in form and function. Each of said pawls has a jaw 1000a which engages when in normal position the ear of a matrix M, and serves to retain the matrix in position ready for being ejected. Each of said pawls has a second jaw 1000b which serves to aid in ejecting the matrices, and also to coact with the jaw 2000a in engaging and retaining the next succeeding matrix, in readiness for being ejected. The jaw 1000b is bevelled as at 1000c and when the pawl is actuated the bevelled surface impinges forcibly against the toe of the matrix M and forcibly impels it forward. At the same instant the jaw 1000a releases the ear of the matrix and permits the matrix to pass. As soon as the ear of the matrix and the toe of the next adjacent matrix have passed the jaw 1000a it is lowered by reverse movement and engages the ear of the next matrix and retains the matrix in readiness for being ejected. The toe on the lower side of the matrix rests upon a ledge 100j of the recess 100f, and the corresponding ear thereof rests upon a ledge 100k of the recess 100e, and the instant that the jaw 1000a of the pawl 1000 impinges against the toe of the matrix, it descends a distance corresponding with the depth of said recess 100f along the inclined surface of the ledge. This inclined surface acts as a cam which tends to advance the matrix with a sudden movement towards the outlet of its channel. At the same time that the said toe of the matrix drops into said recess 100f, the corresponding ear drops into the recess 100e, and the inclined surface of the ledge 100k acts as a cam to move the matrix forward, as it drops into said channel 100c. This lowering of the top of the matrix or the portion upon which the ears are dis-

posed, a distance corresponding with the depth of the recess 100e, insures a clearance of the opposite ear of the matrix by the jaw 1000a also a clearance of the corresponding toe of the next matrix, but before the ear of the next matrix has passed the ledge of the recess, and the jaw 1000a of the pawl 1000, the jaw has been restored to its normal position and engages the ear of the succeeding matrix as it engaged the ear of the first matrix as shown in the drawings, Fig. 2. However if in any case the said jaw 1000a should be restored to its normal position before the toe of the next matrix has passed said jaw, then the toe of the matrix on the lower side thereof, being shorter than the ear thereof, will drop in the recess 100e so that the opposite toe on the upper edge of the matrix will drop under the jaw, 1000a and the matrix will move forward until the ear impinges against the said jaw 1000a. It will be seen that the ear resting on the ledge 100k of the channel 100c, is of such a length that when the ear on the upper edge of the matrix is impinged against the jaw 1000a of the pawl 1000, the ear cannot descend into the channel 100e. Thus the ledge, 100k and recess 100e cooperating with the jaw 1000a of pawl 1000, and the toes of the matrix permit the toes to pass the said pawl and ledge and jaw of said pawl, but they cooperate to prevent the ears of the matrix from passing said jaw and ledge, except when the pawl is moved for releasing the matrix and ejecting it from the magazine. In this manner the first matrix is ejected with certainty by the movement of the pawl 1000, and the second matrix is positioned in readiness for ejection with equal certainty.

To actuate the pawl 1000 a recess 1000d and a tooth 2000h of the releasing bar 2000 is disposed therein whereby the pawl 1000 will be actuated by a movement of the bar 2000.

A channelled member 103, and a second channelled member 104, are superposed upon the top plate 100a, and slots 103a and 104a respectively are provided therein to serve as guides for the ends of the bar, as 2000, and a plate 105 is superposed upon the channel members 103 and 104, to serve as a covering and to also act as a retaining means to keep the bar 2000 and the other bars, some ninety in number, in position. Movement of the bar 2000 and the corresponding bars, is imparted by means of springs, as 103b, and 104b, held in recesses provided in the channel members 103 and 104 respectively, at their lower ends, and having their upper ends disposed in recesses in the bar 2000. Normally the said springs are held under tension, and when the bar is released so as to actuate the releasing pawl, then the spring moves the bar 2000 as required to move said pawl 1000 for ejecting a matrix from the magazine.

Each of the pawls, which may be referred to as numbers 1000 to 1090, are actuated by a different bar numbered respectively as 2000 to 2090, not all shown. The releasing bars are each actuated by the movement of one or more of the releasing rods, 110, 120, 130, 140, 150, 160 and 170, in the manner hereinafter explained.

The releasing bar 2000 has extensions 2000a, 2000b, 2000c, 2000d, 2000e, 2000f and 2000g, and each extension coacts with one of the releasing rods, as shown in Fig. 2 to move the releasing bar.

Each of the releasing rods, is slotted as at 110a, 120a, 130a, 140a, 150a, 160a and 170a. So at every interval where the said rods are spanned by one of the releasing bars the rods are slotted in like manner so that the said extensions upon the said bars may be disposed within said slots when the rods are so adjusted in certain series, as to admit of the movement of said releasing bars as 2000.

In Fig. 2 it will be seen that the slot 120a is disposed at an angle inclined from the extension 2000a, and the extension rests against the body of the rod, while the other slots, are all disposed in parallel relation with the adjacent extensions, so that if the bar 2000 were moved each of said extensions would enter 30 the adjacent slot in the adjacent rod. This illustrates the combination system by which the bars are actuated by the rotation of one or more of the rods. Assuming that bar 2000 is the first of the series of 91 bars, the slots 35 in the rods at this interval, or point on the said rods, are all parallel with said extensions except the slot 110a of rod 110. To release and actuate bar 2000, then, it is necessary to turn rod 110 so as to permit the extension 2000a to enter said slot 110a, when all the other extensions, upon the said bar, will be admitted into the corresponding adjacent slots, and by the force of the springs 103b and 104b the bar is moved towards the left 45 and the pawl 1000 actuated thereby and the matrix M accordingly ejected in the manner above described.

In like manner any number of the slots in the rods may be disposed in the position of slot 110a of rod 110, so that when they are rotated in the same manner as rod 110, then the releasing bar spanning the releasing rods at such interval, will be permitted to move 55 so as to actuate the releasing pawl connected therewith.

The releasing rods are restored to their normal position by the springs as 111, 121, &c., and the releasing bars are restored to their 60 normal position accordingly by the cam action of the slotted rods, as rod 110, and slot 110a, acting on extension 2000a which restores the releasing bar 2000 to normal position after it has been actuated.

65 The cranking elements by which rotation

is imparted to the rods in different combination has been hereinbefore explained.

In Figure 3, is shown a modification of my improvements in releasing means adapted for being disposed below the magazine. It will 70 also illustrate the manner in which the two forms shown could be combined in a double magazine, machine, one having the releasing means below the magazine and the other above the magazine. In Fig. 3 the magazine 75 is designated as 100; the top plate 100a, the lower plate 100b, the plate above the pawl 500c, and the cross-bar adjacent and back of the pawl, 500d and the plate in front of the pawl 500e. The pawl is designated as 1500 80 and the fulcrum as 502. The pawl 1500 has two jaws 1500a and 1500b, a recess 1500c. The upper plate is reenforced by a narrow plate 500f and is curved slightly as at 500g. The structure of the parts of the lower plate, 85 100b, the narrow plate above the pawl 500c and the plate 500e is such that the lower channel of the magazine is recessed as at 500h and 500i. The toe of the matrix M2 normally rests upon the jaw 1500a of the pawl 1500 and 90 the ear of said matrix is engaged by the jaw 1500c of said pawl. When the pawl is actuated the jaw 1500a impacts forcibly against the toe of the matrix, and the bevelled surface of said jaw as 1500b acts as a cam to drive 95 the toe of the matrix forward, at the same instant the jaw 1500c releases the ear of said matrix and the matrix is driven forward and ejected. The toe of the next matrix follows the ear of the matrix ejected, and assumes the 100 position of the toe in the matrix as shown in Fig. 3, resting upon the jaw 1500a of the pawl 1500, and the jaw 1500c of said pawl returns to its normal position in time to engage the ear of the succeeding matrix, which 105 is held in the position of the first matrix, shown in Fig. 3.

To actuate the pawl a releasing bar, designated 3000 is provided and is one of a series of ninety-one, not shown, designated or referred to as 3000 to 3090 inclusive. Said bar 3000 and the series are held in position in a housing as 500j and actuated by spring power as 3000j. A tooth 3000h engages the recess 1500d in the pawl 1500 and when the bar 3000 115 is actuated, it actuates the pawl whereby a matrix is released and ejected in the manner above described.

There are a series of releasing rods, preferably seven in number, similarly as described 120 in the description of the form shown in Fig. 1 of the drawings, but the form of said rods and the releasing bars as 3000 are slightly modified. The rods are designated as 510, 520, 530, 540, 550, 560 and 570, each having an 125 L-shaped recess therein to admit the short extensions of the releasing bar as 3000a, 3000b, 3000c, 3000d, 3000e, 3000f and 3000g.

Returning to Figure 2, it may be explained 130 that it is only when the releasing rods are

all in the position shown in Figure 2 and the rod 110 is rotated that the bar 2000 is actuated as it will be seen, that if any of the other rods are rotated with rod 110 then that rod will lock the bar 2000 against movement since the solid portion of the rod will move into contact with the corresponding extension upon the bar 2000 and lock the bar against movement. Whenever one of the rods in the position of rod 110 is rotated the effect so far as that rod is concerned is to disengage the bar. Whenever a rod in the position of rods 120, 130, 140, 150, 160, and 170, are rotated the effect of any one or all of them is to lock the bar against movement. For every bar there are seven cam elements one on each rod beneath or adjacent each bar. To move or actuate that bar all the cam elements of the rods in the position of the cam element of rod 110 must simultaneously be rotated, and all cam elements of the other rods adjacent to the bar, must remain in the position of the cam elements shown on rods 120, 130, &c. to 170. There is a different arrangement of the cam elements of the seven rods, for each bar, and no combination is ever duplicated. At every movement of one or more rods, some one bar will be released and actuated, and all other bars will be locked by some one or more of the rods by the same movement.

One or a combination of rods may move to release one of the bars.

One or a combination of rods may move to lock one of the bars.

One or a combination of the rods may lock one of the bars when in normal position.

One or more of the rods may when in normal position serve to permit the movement of one of the bars.

With this in mind reference may be had to Fig. 3 of the drawings. It will be seen that rod 510 will have to be rotated 60 degrees or one sixth of a revolution in order to release the bar 3000, but the other six rods 520 &c. to 570 must all remain in normal position in order that the bar 3000 may move. Rod 510 makes its rotation and is restored to its normal position. But now

let us assume that rods 510 and 520 were to be rotated in unison to release the next succeeding bar or some other bar. Now in that case rod 520 would normally be in the same position as rod 510, shown at the interval or channel where the bar were to be released, then the two rods, 510 and 520, rotating together would release the corresponding bar, in the same manner that rod 510 alone released bar 3000. But what prevents bar

3000 from being released, when rod 510 is rotated so as to admit the extension 3000a into the L-shaped recess thereof. When the L-shaped recess rotates so as to admit the extension 3000a, the corresponding L-shaped recess in rod 520, has moved in the same di-

rection as the recess in the rod 510, and thereby the rod opposite or adjacent the extension 3000b has moved into the locking position for said bar 3000 and although rod 510 is in the position for releasing extension 3000a, the extension 3000b is locked against movement.

It may now be seen why the L-shaped recess is provided in the place of the slot shown in Fig. 2. In the case of the slots the rods must rotate a full sixth of a revolution before the extensions 2000a 2000b &c. of the bar 2000, can be fully released or fully locked against movement. Now when some of the rods must be rotated to lock a releasing bar against movement, while another rod, singly or in combination with other rods must rotate to release a bar, it will be seen that where the slot shown in Fig. 2 is employed there will be an intermediate position at which one rod will be between the normal and the extreme positions of rotation for the release, while others will be in the intermediate between the normal position for the release and the extreme position of rotation for locking the bar against movement. Thus; in Fig. 2 rod 110 when it has rotated 30 degrees begins to release the bar and rod 120 in the same degree of rotation has engaged the extension 2000b of the bar 2000 so that it is locked against any movement. Thus when the disengaged rod or rods begin to rotate they must rotate 30 degrees before they engage, and the engaged rods begin to rotate 30 degrees before they disengage the adjacent extension or extensions of the releasing bar, and no releasing bar can move in the direction required for ejecting a matrix when the engaging rods rotate excepting when all the engaging rods of a certain releasing bar, are engaged.

With this in mind reference may be had to Fig. 3 of the drawings. It will be seen that rod 510 will have to be rotated 60 degrees or one sixth of a revolution in order to release the bar 3000, but the other six rods 520 &c. to 570 must all remain in normal position in order that the bar 3000 may move. Rod 510 makes its rotation and is restored to its normal position. But now let us assume that rods 510 and 520 were to be rotated in unison to release the next succeeding bar or some other bar. Now in that case rod 520 would normally be in the same position as rod 510, shown at the interval or channel where the bar were to be released, then the two rods, 510 and 520, rotating together would release the corresponding bar, in the same manner that rod 510 alone released bar 3000. But what prevents bar

3000 from being released, when rod 510 is rotated so as to admit the extension 3000a into the L-shaped recess thereof. When the L-shaped recess rotates so as to admit the extension 3000a, the corresponding L-shaped recess in rod 520, has moved in the same di-

rection as the recess in the rod 510, and thereby the rod opposite or adjacent the extension 3000b has moved into the locking position for said bar 3000 and although rod 510 is in the position for releasing extension 3000a, the extension 3000b is locked against movement.

520, and the locking action is substantially instantaneous, altho the releasing action of the rod 510 is gradual. This prevents any lost motion of the rods when a bar is being released.

After a release has been made the rods are returned to the normal position by spring power as shown in Figure 1 of the drawings in both of the forms herein described. In 10 such case the rods and recesses therein, or slots alike, act as a cam to restore the releasing bars to normal position.

In Figures 14, 15 and 16 the action of a modified form of the rods and the releasing 15 bar described and shown in Figure 3 is illustrated. In Figure 15 rod 1510 is shown in the releasing position, and the bar 3500 has moved into the releasing position. In Figure 16 the rods 1520 and 1530 are shown in 20 the locked position and the rod 1510 in the normal or locked position. It will be seen that had the rod 1510 been rotated with rods 1520 and 1530 as it was shown in Figure 15 still the bar could not move. Figure 14 illustrates 25 how slight a distance the rods as 1520 and 1530 can move before the bar 3500 is completely locked against movement.

Further modification of the cam elements of the releasing rods is shown in Figures 17, 30 18 and 19 wherein the releasing cam elements of the rods are inverted and a quicker release of the bar is made possible since, by this device the release will be complete when the rod has rotated for 15 to 25 degrees whereas with 35 the two forms shown in Figures 2 and 3, and 14 to 16 of the drawings, a complete release is not effected until the releasing elements have rotated at least 60 degrees or one sixth ($\frac{1}{6}$) of a revolution.

40 In Figures 17 to 19 inclusive, the releasing bar is designated as 4000 and the extensions as 4000a, 4000b and 4000c, and the releasing bars, as 510a, 520a and 530a.

The locking cam-elements or L-shaped recesses in rods 1520a and 1530a, are the same as in Figures 14 to 16, but the extension 4000a is inclined at the lower part thereof, as 4000d, and the recess in rod 1510a is inverted, and instead of having sharp angles, the angles are 45 rounded, as at 1500e and 1500f. As the rods are strong and held rigidly against rotation when not being released or rotated for locking by the mechanism of the machine, a small surface is ample to prevent the bar from moving when resting against the rod. But when it is desired to release the bar, the movement, of 15 degrees or less is considered sufficient for a complete release, and at the same time a movement of 5 or 10 degrees of the rods 50 which are being rotated to lock the bars against movement will have been completed.

The rounded angles, as 4000d of the extension 4000a, and 1500e and 1500f of the rod 1510a, make possible the cam action necessary to restore the bar to its normal position

and to permit the rod 1510a to return to its normal position while camming the bar 500a back to its normal position.

In Figure 10 of the drawings a modification of my permutation releasing rods is 70 shown, in which they are employed as part of an adaptation of the cam-roller releasing principle, wherein a timed escapement of a form often used is employed.

The cam bar 5000 is employed to actuate 75 the release 600a, said cam bar is carried in slots or spaces in a comb as 601, 602, and 603, and is supported upon springs, as 604 and 605, which have both vertical and lateral movement. One end of a spring is held in the 80 comb member as at 601a and 602a and the opposite end is bifurcated, as at 601b, and 602b and seated in a recess in the cam bar, as at 5000a and 5000b, and extensions of said cam bar, as 5000c and 5000d engage the said 85 springs, whereby the springs are compressed to permit movement of the cam bar, and the cam bar is moved by the springs as required to bring the cam-roller 5000p, into engagement with the roller 606, 90 whereby the releasing pawl 600a is actuated. The spring 600b returns pawl 600a to normal position.

The releasing rods, as 610, 620, 630, 640, 650, 660 and 670, only a part whereof is shown, 95 are provided with tooth members as 611, 621, and 631, etc., which engage recesses 5000f, 5000g, and 5000h, etc., and tooth members 611a, 621a, 631a, etc., adapted to engage recesses 5000l, 5000m, 5000n, etc. One or the 100 other of each pair of teeth, as 611 or 611a, 621 or 621a, is cut away at each channel in accordance with the combination series hereinbefore mentioned, in the same way that the bars 110 to 170, shown in Fig. 2 are cut. 105 The rods 610, 620, etc., are kept in normal position and operated in the same manner as rods 110, 120, etc., are kept in normal position by springs 112, 122, etc., and operated by magnets. In Fig. 10 the rod 630 is in the engaged position and the rods 610 and 620 in the disengaged position so that when rod 630 is rotated the cam bar 5000 will be disengaged and the springs 604 and 605 force the cam 110 5000p into engagement with the roller 606. 115 The principle of operation in this adaptation of the releasing rods is by the combination movement of the releasing means, as in the other forms herein shown. The release is actuated by the spring power and the cam bars are restored by the cam and cam roller so that the parts are disposed in position for another release.

A further modification of my permuted releasing rods is shown in Figures 9, 11, 12 125 and 13 in which the magazine is designated as 700, and the releasing pawl is the same as shown in Fig. 10, and is designated as 700a, the cam bar 6000, disposed in combs as 701, 702 and 703, having springs 704 and 705 130

arranged in all details substantially the same as in the modification of my invention shown in Fig. 10. A cam is provided on the end of the cam bar, as 6000e for engagement with the roller 706.

The releasing rods, employed in this adaptation of my invention are designated as 710, 720, 730, 740, 750, 760 and 770. Said rods are movable in longitudinal direction, by means of cam-rods, as 800, in Fig. 13. The releasing rods, are slidably held in the members 6000f and 6000g and a recess 6000h is provided in the member 6000f, which serves as a gage to limit the movement of the releasing rod, as 710, as follows. The end of said rod 710 is rounded as at 711, so that the cam-rod 800 will act therein properly. On the opposite end of the releasing rod, is a threaded portion, as 712, and a coil spring 713, normally holds the releasing rod at the extreme position to the right. Said threaded portion is seated in a bore, in the member 6000f and a nut 714 is disposed or threaded thereon, so that by rotating said nut, the movement of the releasing rod will terminate at any desired position. A guide as 6000j is provided for retaining the cam rods 800, 810, 820, &c. in position to act upon the releasing rods to force them to the left against the force of the springs 704, 705 &c. and said springs after the rods have been actuated restore them to the normal position. In the complete magazine there are 91 cam bars numbered for convenience 6000 to 6090 inclusive, and on each are seven teeth as 6000k, 6000l, 6000m, 6000n, 6000o, 6000p, and 6000q, and on the releasing rods are coacting teeth as 710a, 720a, 730a, 740a, 750a, 760a and 770a. The said teeth on said releasing rods are arranged to engage the teeth on the cam bars in combination corresponding with the combination series hereinbefore mentioned in relation to the adaptations and modifications of my invention hereinbefore described.

When one or more of the said releasing bars is moved by the cam action of the rods 810, 820, 830, 840, 850, 860 and 870 the teeth on the said rods are respectively moved out of engagement with the teeth of the said cam bars so that the cam bar is forced by the spring means described towards the roller 706, and the cam as 6000e thereon forces it back into its normal position. In the meantime the movement of the cam bar has actuated the release and a matrix has been ejected and the spring 700b has restored the release 700a to its normal position and the parts are in position for another operation for ejecting another matrix from the same channel or any other channel of the magazine.

It is not necessary that the releasing rods be made integrally as indicated in the drawings, but on the contrary it may be preferable to make each of the cam elements or en-

gaging elements thereof in the form of a separate plate of the correct form with a central angular opening therethrough so that they may be disposed at the proper intervals upon an angular rod with which they may be rotated as required to produce the required cam action. Another way they might be formed is: A slotted recess extending from one side might be provided in each separate cam element so that they could be slidably disposed upon an angular rod at the proper interval as shown in my pending application hereinbefore referred to.

While I have described and shown my invention as illustrated in the drawings, I do not wish to be understood as limiting myself to the particular forms of construction shown and described, but reserve the right to depart therefrom within the reasonable scope and spirit and objects of the invention, making use of any mechanical equivalent whereby the purposes and objects of my invention may be attained.

Having thus described my invention what I claim as new therein and desire to secure by Letters Patent of the United States is:

1. Typographical escapement operating mechanism including, a releasing pawl of the character described, a releasing bar adapted to longitudinal movement for actuating said pawl, spring means for actuating the releasing bar; engaging elements of the said releasing bar, for engaging other engaging elements arranged in combination series upon a plurality of combination rods; means for moving said rods whereby the engaging elements on one or more of the rods will disengage the engaging elements upon the releasing bar; and timing means regulating the restoration of the releasing bar to its normal position.

2. In a typographical machine, a releasing bar connected with each escapement pawl of a magazine, each of said releasing bars having engaging elements for engaging with one or more engaging elements, in a series, one upon each of one or more movable rods arranged in combination series, whereby the movement of the rods in each combination will allow a corresponding releasing bar to move longitudinally and actuate its pawl for the ejection of a matrix from a channel of the magazine; and timing means upon said releasing bar whereby the releasing mechanism is restored to normal position in readiness for another operation in a predetermined length of time.

3. In a typographical machine, a pawl fulcrumed at each channel of a magazine for retaining and ejecting a matrix therein; a releasing bar, adapted to move longitudinally for actuating each of said pawls, spring means for actuating said releasing bars; a plurality of permutation rods, each having a series of engaging elements thereon for en-

gaging similar elements on the releasing bars, whereby one of the releasing bars may be released when a predetermined series of the permutation rods are moved, and means for 5 timing the restoration of the releasing bars to their normal position.

4. Releasing means for circulating matrices in a channel magazine typographical machine; including, a plurality of permutation rods, means for actuating said rods, and a plurality of releasing pawls, one for each channel of the magazine of the machine, means directly controlled by the permutation rods for actuating the releasing pawls, and 10 means for timing the restoration of the means for actuating the pawls to their normal position.

5. In a typographical machine, a releasing bar connected with each escapement pawl 20 of a magazine, spring means for actuating said releasing bar; spring means for restoring the pawl to normal position; in combination with an eccentric rotary cam on the releasing bar and a cam roller whereby said 25 releasing bar is restored to normal position.

6. In a typographical machine, a releasing bar connected with each escapement pawl of a magazine, said releasing bars arranged in a plane parallel with the magazine and 30 each releasing bar substantially parallel with the channels thereof; spring means for actuating the releasing bars and spring means for restoring to normal position each of the pawls; in combination with an eccentric cam 35 rotatably mounted upon one end of each releasing bar, and a roller arranged transversely of the magazine, adapted for engaging the several rotary cams and restoring the releasing bars to their normal position, 40 in a predetermined length of time after they are released, and a series of movable rods, adapted for being moved in combinations, whereby the releasing bars are disengaged so that the spring means may actuate them.

45 7. In a typographical machine, a plurality of movable rods, adapted to be moved in different combinations, means for actuating said rods, a separate longitudinally movable bar for actuating a releasing pawl in each 50 channel of a magazine containing matrices, whenever one or more of said movable rods are actuated, and means for readjusting all of the parts within a predetermined time when a matrix has been released.

55 8. In a typographical machine, a releasing member connected with each escapement pawl of a magazine, means upon a plurality of engaging means upon the releasing members, whereby one of the releasing members 60 will be released so as to actuate a predetermined releasing pawl, and thereby eject a predetermined matrix, when one or more of the movable rods are moved in unison in combinations; in combination with a continuously 65 rotating roller, and a rotary eccentric

cam held on each of the releasing members adapted for engaging the said roller whereby the said releasing member is restored in a predetermined time to its normal position of engagement with the movable rods.

9. In a typographical machine, a releasing bar connected with each escapement pawl of a magazine, arranged substantially parallel with the channels of said magazine; a plurality of releasing rods movably held 70 in engagement with the releasing bars, means whereby one of the releasing bars may be disengaged when one or more of said releasing rods are moved in unison in combination, 75 whereby a predetermined pawl may be actuated and the corresponding matrix released from the magazine; spring means for actuating the releasing bars when disengaged, spring means for restoring the pawl when it has been actuated and spring means for 80 restoring the releasing rods to normal position after being actuated, means for actuating the movable releasing rods in combinations of one to seven; in combination with a rotating roller and an eccentric rotatable 85 cam upon each of the releasing bars, adapted for engaging with said roller, whereby the 90 said releasing bars will each be restored in a predetermined time to normal position after being actuated.

10. In a typographical machine, a magazine containing a plurality of channels containing each a number of classified matrices; a plurality of pawls in said magazine, one for each channel adapted for retaining and 100 ejecting matrices from said magazine when actuated, a plurality of releasing bars, one arranged substantially parallel with each of said channels and adapted to actuate the pawl disposed in such channel, spring means for actuating the releasing bars, and spring means for restoring the pawl to its normal position, each of said releasing bars having 105 engaging elements thereon for engagement with an engaging element upon one or more releasing rods; a plurality of movable releasing rods, each having engaging elements for engagement with one or more of the engaging elements upon one or more of the several releasing bars, whereby a predetermined 110 releasing bar may be released so as to actuate a predetermined releasing pawl and thereby eject a predetermined matrix, when a predetermined combination of the movable 115 releasing rods are actuated in unison in any combination, in combination with an eccentric rotatable cam held upon each of the releasing bars and adapted for engaging a rotatable rod held on the magazine and continuously rotating, whereby each of the releasing bars may be restored to normal position in a predetermined length of time after a matrix has been ejected from the magazine.

11. Selective mechanism including a magazine containing a classified series of let- 120

tered, numbered or otherwise distinguished elements; means for regulating said elements, a plurality of selective rods movable singly or in combination in unison, means for actuating said rods, means for restoring said rods to normal position after they are actuated, a plurality of bars arranged in a plane parallel with said rods, engaging elements at different spaced intervals upon the several rods, coacting engaging elements upon the bars, whereby one of said bars may be actuated with every movement of one or more of said rods, a pawl adapted to be actuated by each of said bars and means for retaining said bars and said pawls to normal position after they have been actuated.

12. Selective mechanism including a plurality of lettered, numbered or otherwise distinguished elements, means for movably retaining said elements; a plurality of pawls each adapted for controlling one class of said elements; means for actuating said pawls singly so as to actuate one of said elements at a time, a plurality of selective bars, each being adapted for controlling one of said pawls, a plurality of movable rods, arranged in a plane parallel with said bars, engaging elements upon said bars, and engaging elements on said rods, whereby one of said bars may be actuated with every movement of one or more of said rods, means for moving said rods, spring means for restoring said pawls, bars and rods to normal position after they have been moved.

13. Selective mechanism including a plurality of lettered, numbered or otherwise distinguished elements, means for retaining and controlling said elements in guides in readiness for being moved or actuated; a pawl adapted for regulating each class or series of said elements, means for actuating said pawls singly whereby one of said elements may be actuated thereby; a plurality of movable bars each adapted for regulating and controlling or actuating one of said pawls, spring means for moving said bars, and a rotary cam on each of said bars whereby the said bars may be each restored to normal position in a predetermined space of time, a plurality of rods, movable singly or in any combination, engaging elements, at spaced intervals on each of said rods, and engaging elements on each of said bars adapted to coact with the engaging elements on one or more of said rods when one of said rods moves singly or any combination of said rods moves in unison; means for actuating said rods, magnetic means adapted to be actuated by a keyboard, adapted to actuate the means for actuating said rods, and means for restoring each part to its normal position after it has been actuated.

14. Selective mechanism including a plurality of numbered, lettered or otherwise distinguished elements, means for retaining said

elements in classes or series in readiness to be actuated or used, a pawl adapted for actuating the elements of each class, spring means for actuating said pawl, a bar for actuating each of said pawls, spring means for actuating each of said bars, a plurality of movable rods, adapted to be moved singly or in unison in any combinations, means upon the rods, adapted to coact with means upon said bars, whereby one of said bars will be actuated whenever one or any combination of said bars is actuated, spring means for restoring said bars to normal position after they have been actuated, an eccentric rotary cam adapted for restoring said bars to normal position after they have been actuated, rods adapted for moving or actuating the first mentioned rods, guides for said rods, means for regulating the movement of the first rods and for lengthening or shortening the last mentioned rods, magnetic means whereby the said rods may be actuated from a keyboard.

15. Selective mechanism including a plurality of numbered, lettered or otherwise distinguished elements, movably disposed in a plurality of guides and arranged in series or classes, means for selectively actuating or employing one of said elements singly comprising a releasing or actuating pawl for each class or series, a bar adapted for actuating each pawl, rotary cam means and spring means for actuating and restoring said bar to its normal position, a plurality of movable rods, adapted to be actuated singly or in combination in unison, engaging elements on each of the bars, and coacting engaging elements at spaced intervals on one or more of said rods adapted for engaging the engaging elements upon the bars, means for adjusting the movement of said rods, and rods for actuating said first rods, guides for the last mentioned rods and electromagnets, adapted to be actuated from a keyboard.

16. In a machine, selective mechanism including a plurality of lettered, numbered or otherwise distinguished elements, movably held in a magazine or series of guides, in classified groups or series, a pawl for each class adapted for actuating one of said elements singly, a bar substantially parallel with the magazine or the guides thereof for each pawl and adapted to actuate said pawl, rotary cam means for restoring the bar to normal position and a plurality of movable rods, disposed in a plane parallel with the bars and the magazine or guides and adapted to be actuated.

17. In a typographical machine, escapement operating mechanism, comprising parallel rods and parallel transverse bars having projections to engage cams on said rods, each bar moving longitudinally to operate an escapement when released directly by said cams.

18. In a typographical machine, escape-

ment operating mechanism, comprising parallel rods and parallel transverse bars having projections to engage cams on said rods, each bar moving longitudinally to operate an escapement when released directly by said cams, and timing means on said bars.

19. In a typographical machine, escapement operating mechanism, comprising parallel rods, parallel transverse bars having projections to engage cams on said rods, each bar moving longitudinally to operate an escapement when released directly by said cams, and timing means on said bars, comprising rotary cams adapted to engage a continuously moving surface.

Signed at Brooklyn, in the county of Kings, in the city and State of New York this twenty second day of September A. D. 1926.

ROY EMERY.
